US00D927729S

(12) **United States Design Patent** (10) Patent No.: **US D927,729 S**
Peak et al. (45) Date of Patent: **** Aug. 10, 2021**

(54) **BUILDING**

- (71) Applicant: **Apple Inc.**, Cupertino, CA (US)
- (72) Inventors: **Christopher Daniel Peak**, Oakland, CA (US); **Jonathan P. Siegel**, San Francisco, CA (US); **Christopher M. Green**, Woodside, CA (US); **David Nelson**, London (GB); **Stefan Behling**, London (GB); **David Summerfield**, London (GB); **James McGrath**, Cupertino, CA (US); **Peter Han**, New York, NY (US); **Adrian Parkinson**, New York, NY (US)
- (73) Assignee: **Apple Inc.**, Cupertino, CA (US)
- (**) Term: **15 Years**
- (21) Appl. No.: **29/680,431**
- (22) Filed: **Feb. 15, 2019**

Related U.S. Application Data

- (63) Continuation of application No. 29/617,035, filed on Sep. 11, 2017, now Pat. No. Des. 841,189, which is a continuation of application No. 29/553,504, filed on Feb. 2, 2016, now Pat. No. Des. 797,305.

Primary Examiner — Manpreet S Matharu*Assistant Examiner* — Suzanne E Tisdell(74) *Attorney, Agent, or Firm* — Sterne, Kessler, Goldstein & Fox P.L.L.C.(57) **CLAIM**

The ornamental design for a building, as shown and described.

DESCRIPTION

FIG. 1 is a top front perspective view of a building showing the claimed design;

FIG. 2 is a front view thereof;

FIG. 3 is a left side view thereof;

FIG. 4 is a right side view thereof; and,

FIG. 5 is a top view thereof.

The oblique shade lines in the figures show transparency or translucency.

Portions of the building not shown in the figures form no part of the claimed design.

The broken lines in the figures show portions of the building that form no part of the claimed design.

1 Claim, 5 Drawing Sheets(56)
